[57] **CLAIM**

The ornamental design for an overlay scroll work unit for a ceiling fan, as shown and described.

DESCRIPTION

FIG. 1 is a bottom view of overlay scroll work unit for a ceiling fan embodying my new design, the top being a mirror image of that shown; the broken line showing of a ceiling fan, is for illustrative purposes only and forms no part of the claimed design;

FIG. 2 is a perspective view of overlay scroll work unit for a ceiling fan; the broken line showing of a ceiling fan, is for illustrative purposes only and forms no part of the claimed design; and,

FIG. 3 is a front view of overlay scroll work unit for a ceiling fan; the broken line showing of a ceiling fan is for illustrative purposes only and forms no part of the claimed design.
